UNITED STATES PATENT OFFICE.

JOHN T. McTARNAHAN, OF BOSTON, MASSACHUSETTS, ASSIGNEE TO RALPH H. CA-
HOUET, TRUSTEE IN BANKRUPTCY OF McTARNAHAN FUEL OIL BURNING COR-
PORATION, BANKRUPT, OF BOSTON, MASSACHUSETTS, A CORPORATION OF MASSA-
CHUSETTS.

FURNACE.

Application filed December 21, 1921. Serial No. 523,857.

To all whom it may concern:

Be it known that I, JOHN T. McTARNAHAN, a citizen of the United States, residing at Boston, in the county of Suffolk and 5 State of Massachusetts, have invented an Improvement in Furnaces, of which the following description, in connection with the accompanying drawings, is a specification, like characters on the drawings representing 10 like parts.

The invention to be hereinafter described relates to furnaces for boilers and other uses, and more particularly to fuel oil furnaces.

15 In furnaces of this type, a burner or burners may be employed for projecting atomized fuel oil into the furnace, suitable means being provided for regulating the flow of fuel according to whether high or 20 low heating effect is desired.

It has been customary to inject the fuel oil flame into a large open combustion chamber similar to that of a coal burning furnace, but with the grate removed. It has 25 been found that when the regulator reduces the fuel supply for low heating effect, the flame issuing from the burner frequently is puffed out or extinguished. This was due to lack of sufficiently high temperature 30 in the furnace, and to lack of proper protection for the flame from eddies and drafts in the furnace. In some instances on reduction of the fuel supply, the flame was not 35 reduced to such an extent as to cause the same to be extinguished, but it was found that the flame would lose its proper direction for proper heating effect.

As a result of the aforesaid conditions, 40 unconsumed particles of oil would fly off, strike the heating surfaces of the boiler, and develop obnoxious gases which would escape through the stack and fill the neighborhood with a bad odor. This caused frequent complaints from persons living in the 45 vicinity and from municipal health departments. Also, the unconsumed particles would deposit soot on the heating surfaces and other parts in the interior of the boiler. These conditions materially reduced the efficiency of the combustion, and required an 50 excessive amount of air to support the combustion, which, as is well known, is one of the principal factors in causing inefficient combustion of fuel oil.

Sometimes if the temperature within the 55 furnace was not too low, the flame would relight, thereby causing a sharp explosion liable to frighten the caretaker of the boiler, and the people in the building in which the 60 boiler is installed.

One of the purposes of the present invention, therefore, is to provide a furnace which will overcome the aforesaid objectionable conditions, that is, a furnace which will store up or retain sufficient heat to prevent 65 the fire from being snuffed out or extinguished when regulation is used for low heating effect; a furnace that will protect a low flame from eddies and drafts, and thus prevent the flame from being puffed out or 70 extinguished or from losing its proper direction; a furnace which will store up or retain sufficient heat to burn all of the oil projected from the burner, and thereby 75 materially reduce deposit of soot on the heating surfaces, and prevent malodorous gases from escape through the stack into the neighborhood; and a furnace which will prevent explosions therein. In other words, 80 the purpose is to provide a furnace which will result in maximum efficiency of combustion of the fuel oil, reduce the fuel oil consumed, and increase the efficiency of the boiler in which the furnace is used.

In carrying these features of the invention into practical effect, in the present instance, a furnace is provided having a combustion chamber so formed and arranged in relation to the burner, that the walls of the chamber protect the flame, when regulated for low heating effect, from eddies and drafts in the furnace. The walls and arch or roof of the chamber are highly heated by the flame issuing from the burner, so 90 that the heat stored in the walls, radiates back into the chamber and contributes to efficient combustion of the fuel oil when the flame is regulated for both low and high heating effect. The combustion chamber is 95 of substantial length, and the flame must pass therethrough before coming in contact with the water tubes or other surfaces of the boiler to be heated. As a consequence, the flame path is desirably lengthened, and 100 combustion of the gases is practically complete before entering the stack.

When the combustion chamber is formed of ordinary refractory bricks, the time,

labor and expense of construction have been objectionable, due to the importance of constructing the chamber of proper form and size. Usually the ordinary mason cannot be relied upon to construct the chamber properly, and therefore, supervision of his work has been required.

Another purpose of the present invention, therefore, is to provide a combustion chamber which may be constructed of specially formed ceramic blocks which practically determine the form and size of the combustion chamber. These blocks may be formed for interlocking relation with uniting elements which will securely hold the blocks in assembled relation. The construction is such that the form and size of the blocks may be standardized, thereby enabling them to be quickly and easily assembled properly to form the combustion chamber, and without requiring the services of expensive, skilled labor.

With the aforesaid and other purposes in view, the character of the invention may be best understood by reference to the following description of one good form of the invention shown in the accompanying drawings, wherein:

Fig. 1 is a front elevation of a boiler equipped with a furnace embodying the invention;

Fig. 2 on an enlarged scale is a perspective view of portions of the blocks of the walls of the furnace, illustrating the means for connecting the blocks;

Fig. 3 is a vertical longitudinal section taken on line 3—3 of Fig. 1; and

Fig. 4 on an enlarged scale is a vertical transverse section through the furnace. The furnace is suitable for a variety of boilers, such, for example, as horizontal, vertical, water tube, steam tube, Dutch oven, front or rear fired; and other types of boilers, but for purposes of illustration, in the present instance, the furnace is shown in a sectional water tube boiler.

This boiler comprises a cast iron base 1 formed of plates 3 having strengthening flanges 5.

Mounted on opposite sides of the base are hollow sections 7 which extend upward and have portions 9 extending horizontally inward to form the top or crown of the boiler.

Above the top portions of the hollow sections is a steam drum 11 connected to the hollow sections by nipples 13 which may be disposed in staggered relation. Adjacent the lower ends of the hollow sections are side drums 15 connected to the hollow sections by nipples 17. One of the side drums may be connected by a pipe 19 with the steam drum, said pipe being provided with the usual water gage 21 and valves 23.

Mounted on the base is a hollow front

wall 25 connected by a nipple 27 with the steam drum, said wall being provided with doors 29 and 31, furnishing access to water tubes and other parts to be described, within the boiler.

At the rear of the boiler is a hollow wall 33 connected to the steam drum by a nipple 35. This wall is provided with an opening 37 communicating with a chamber 39, communicating in turn with a pipe 41 adapted for connection with the chimney or stack, said pipe being provided with the usual damper 43.

Rows of water tubes 45, 47 and 49, may be threaded into the hollow wall sections 80 and project horizontally inward toward one another beneath the top of the boiler. The tubes 45 are in spaced relation to allow the gases of combustion to envelope and pass upward between the same. The tubes 47 of the intermediate row are also in spaced relation, but these tubes are connected by wings 51, with the exception of the tubes 47^a which are spaced to provide passages 53, allowing the gases of combustion to pass upward to the top row of tubes 49, which are in spaced relation to allow the gases of combustion to envelope and pass between them. The construction is such that the gases of combustion coming from the combustion chamber to be described, are caused to pass along the lower row of tubes 45 toward the front of the boiler, thence upward through the spaces 53 between the tubes 47^a of the intermediate row of tubes, and thence upward between the upper row of tubes 49. The gases then flow rearward beneath the top portions 9 of the hollow sections, and thence into the chamber 39 and the pipe 41 leading to the chimney stack.

The boiler thus far described may be of usual well known construction in its principal features, and therefore, it is unnecessary to describe the same further in detail herein.

One of the end walls of the boiler, in the present instance the front wall, may be provided with a door 55 having an aperture receiving a fuel oil burner 57 of well known construction, said burner, in the present instance, being provided with a collar 59 secured to the door by bolts 61. The fuel oil and atomizing fluid may be conducted from sources of supply to the burner by usual means unnecessary to show and describe herein.

As stated, one of the purposes of the present invention, is to provide a furnace constructed and arranged to promote efficient combustion of the fuel oil. This furnace is formed to provide a combustion chamber 63 of substantial length, and having solid, thick, heat storing walls and a crown or arch which are sufficiently near to the flame

issuing from the burner to be highly heated thereby. The heat stored in the walls and arch will radiate back into the combustion chamber and contribute to efficient combustion of the fuel.

This furnace may be constructed of suitable materials, but in the present instance, it is formed of ceramic refractory blocks which may be of a form and size substantially to 10 determine their assemblage and the shape of the combustion chamber.

To accomplish this, in the present instance, a series of floor blocks 65 is provided, of oblong shape and preferably of a length 15 sufficient to extend from one side of the boiler to the other.

Mounted on the floor blocks 65 are side blocks 67, certain of the side wall blocks 67 being formed to present abutments 69. 20 Mounted on these abutments and bridging the side blocks are arch blocks 71. In the present instance, three of these arch blocks are provided, but it will be understood that the number thereof may be varied according 25 to the length of combustion chamber required.

In alignment with and projecting rearward from the side blocks 67 are additional side blocks 73 projecting to the rear wall of 30 the boiler and rising somewhat above the top of the combustion chamber.

Extending between the side blocks 73 is a rear or baffle wall comprising a lower block 75 having a curved deflecting surface 77, intermediate blocks 79, and an upper block 81 having a curved deflecting surface 83 extending toward the combustion chamber. 35 Mounted on the upper block 81 is a top block 85.

40 At the front of the boiler is a wall comprising a series of blocks 87, which may be supported by the front floor block, and constitute the front wall of the combustion chamber. Certain of these front wall blocks 45 may have an aperture 91 to receive the inner end of the burner, said aperture being lined by a collar 93.

When the burner is in active firing position, the door 55 is closed and the burner 50 projects inward somewhat beyond the collar 93. When the burner is inactive, the door is swung open, thereby moving the burner outward where it will be protected from residual heat in the combustion chamber.

55 Air for supporting combustion of the fuel may be admitted into the combustion chamber through an elongated port 95 formed in the lowest block of the front wall of the chamber and in the front base plate, said 60 port being provided with a hinged damper 95 which may be manually regulated or automatically regulated by means unnecessary to disclose herein.

As stated, another purpose of the invention is to provide means for connecting the

blocks of the furnace to hold the same securely in assembled relation. To accomplish this, in the present instance, the blocks are provided with opposed grooves 97 which may flare inwardly or have bases wider than 70 their mouths. Mounted in the opposed grooves of the blocks are locking elements, in the present instance, in the form of bars 99 which desirably may be of I-bar cross section having heads 101 for interlocking engagement with the grooves 97.

In assembling the blocks, they may be placed in proper superposed relation with the grooves of adjacent blocks in opposed relation, and then the interlocking bars may 80 be slid longitudinally into the grooves, thereby securely to hold the blocks against relative movement. Preferably the interlocking bars do not have a close fit with the 85 grooves, but are somewhat smaller than said grooves to permit expansion and contraction of the bars under temperature changes, without causing displacement or breakage of the blocks. The blocks may be numbered if 90 desired to facilitate their assembly.

The burner is located at one end of the combustion chamber, and the flame passes therethrough and issues from the opposite open end of the chamber. The disposition of the chamber with relation to the water tubes or surfaces may vary in different types 95 of boilers, but the chamber should be so located that the gases of combustion will be delivered by the open end of the chamber at a point where the gases will start on a flame path, which will bring them in contact with all of the tubes or other heating surfaces. In the present instance, the gases are delivered at the rear end of the furnace to the rear tubes of the lowest row of water tubes. 100 They pass thence forwardly surrounding the lowest row of tubes and in contact with the under surfaces of the intermediate row of tubes. Then they pass upward through the spaces 53 and flow rearward about the top row of tubes toward the stack opening. 105

110 By my invention a furnace is provided which desirably cooperates with the burner to store up heat in the walls and arch or roof of the combustion chamber. This heat is radiated back into the chamber to maintain a temperature therein sufficiently high to insure combustion of the oil when regulated for low heat effect. Deposit of soot on the heating surfaces is reduced, and escape of 115 malodorous gases from the stack, and explosions in the furnace are prevented. The combustion chamber so surrounds and protects the flame from eddies and drafts in the furnace, that the flame is always properly directed without localization of the heat therefrom. Also, it is unnecessary to introduce excess air into the combustion chamber, but, on the contrary, a proper amount of air 120 is supplied for most efficient combustion of 125

the fuel oil. A further advantage is in the fact that the combustion chamber retains the heat so well that when the flame is reduced or entirely shut off, the parts of the boiler 5 in which the furnace is used, cool slowly and thereby prevent rapid contraction thereof which might cause injury thereto.

The specially formed ceramic blocks and their uniting elements enable the furnace 10 to be quickly, easily and properly constructed by cheap labor in minimum time and with minimum expense. It will be understood, however, that it is not indispensable that the furnace shall be constructed of ceramic 15 blocks, but, on the contrary, it may be desirably constructed of metal or other material if desired.

It will be understood that the invention is 20 not limited to the specific embodiment shown, and that various deviations may be made therefrom without departing from the spirit and scope of the appended claims.

What is claimed is:—

1. In a furnace, a combustion chamber of 25 substantial length comprising side walls, a crown, an end wall, and an upright baffle wall having an upper deflecting portion extending a slight distance toward the crown, said baffle wall being spaced from the crown 30 to leave an outlet, and said side walls having upstanding portions projecting above the crown between the baffle and the end of the crown; and a fuel oil burner entered through the end wall for projecting its flame into the 35 combustion chamber toward the baffle wall, that the baffle wall and the upstanding portions of the side walls may direct the gases of combustion upward; the side walls and

crown of said combustion chamber being of solid, thick, heat storing ceramic material 40 and closely related in respect to the burner so as to become highly heated by the flame from the burner and store up heat to be radiated back into the combustion chamber and promote combustion of the fuel oil. 45

2. In a furnace, a combustion chamber of substantial length comprising side walls, a crown and end walls, one of the end walls being spaced a substantial distance from one end of the crown to leave an outlet, said side 50 walls and crown being formed of solid, thick blocks of ceramic material specially formed to determine the shape and size of the combustion chamber, certain of said side wall blocks being formed to provide abutments 55 for supporting the crown blocks, the side wall and crown blocks having opposed horizontal grooves therein, metallic uniting elements in said grooves, said elements and grooves being formed for interlocking engagement, thereby to secure the blocks in assembled relation; and a fuel oil burner entered through one of the end walls for projecting its flame through the combustion 60 chamber toward the opposite end wall, that the gases of combustion may be deflected by the latter up through the outlet; the side walls and crown of the combustion chamber being closely related in respect to the burner so as to be highly heated by the flame and 65 store up heat to be radiated back into the combustion chamber and promote combustion of the fuel oil. 70

In testimony whereof, I have signed my name to this specification.

JOHN T. McTARNAHAN.
